Primary Examiner — Kevin K Rudzinski*Assistant Examiner* — Kathleen L Jones(74) *Attorney, Agent, or Firm* — Muncy, Geissler, Olds & Lowe, P.C.(57) **CLAIM**

The ornamental design for a frame for a vehicle, as shown and described.

DESCRIPTION

FIG. 1 is a front elevational view of a frame for a vehicle showing my new design;

FIG. 2 is a top plan view thereof;

FIG. 3 is a right side elevational view thereof;

FIG. 4 is a left side elevational view thereof;

FIG. 5 is a rear elevational view thereof;

FIG. 6 is a bottom plan view thereof;

FIG. 7 is a top, front, left perspective view thereof;

FIG. 8 is top, rear, right perspective view thereof;

FIG. 9 is a cross-sectional view taken along line 9-9 of FIG. 3; and,

FIG. 10 is a perspective view of the frame for a vehicle shown in an environment of use depicted in broken lines. The broken lines illustrate environmental structure which forms no part of the claimed design.

1 Claim, 10 Drawing Sheets(56)
